UNITED STATES PATENT OFFICE

JOSEPH M. SCHAEFER, OF CHICAGO, ILLINOIS, ASSIGNOR TO A. G. SPALDING & BROS.,
A CORPORATION OF NEW JERSEY.

BASE-BALL MASK.

1,186,442.

Specification of Letters Patent. Patented June 6, 1916.

Application filed April 4, 1916. Serial No. 88,965.

To all whom it may concern:

Be it known that I, JOSEPH M. SCHAEFER, a citizen of the United States, whose residence is 818 East Sixty-fourth street, Chicago, Illinois, have invented certain new and useful Improvements in Base-Ball Masks, of which the following is a specification.

The invention concerns particularly means 10 for holding the base-ball mask in position upon the head of the user, in such manner as to avoid displacement, should the user make a quick movement, and it concerns also means whereby the frame is rendered of 15 stronger construction.

The invention consists in the features and combination and arrangement of parts hereinafter described and particularly pointed out in the claims.

20 In the accompanying drawings—Figure 1 is a side view of a mask embodying the invention; Fig. 2 is a plan view partly in section; Fig. 3 is a view of a detail; Fig. 4 is a sectional view of the casing with the spring 25 and rod in place; Fig. 5 is a detail view of the split wire joint.

In these drawings the main frame and pad of the mask are of substantially ordinary construction. This mask ordinarily is held 30 in position by means of an elastic strap, passing around the back of the head, but owing to the freedom with which this elastic strap yields or stretches an objection has been experienced in that the mask has become displaced on the head of the user when he makes a quick movement, and as such mask is used by the catcher the displacement referred to will disconcert him at a critical 35 moment and interfere with his proper vision 40 and cause him to make a misplay, such as a bad throw.

To avoid the use of this objectionable elastic or yielding connection is one object of my invention, which consists in employing 45 an inelastic strap or band 1 to pass around the head of the user, the ends of this strap being attached to rods or members 2 slidably mounted in casings 3, which are attached to the frame of the mask. Within these casings 50 springs 4, of spiral form are mounted, which tend to keep the rods pressed toward the front of the casings. In other words, backward movement of the rods can take place only by compressing the springs. 55 These springs therefore hold the inelastic

strap or band in proper contact with the head of the catcher and will prevent slipping of the band at a critical moment. The tension of the holding means may be adjusted by the buckle and strap connection at 5.

60 While the spring casings may be mounted on the frame in various ways, and come within the broad scope of my invention, I have provided a mounting having special advantages in the organization necessary in 65 devices of this character. This mounting consists in a pivotal connection between the casing and the frame which will allow the casing to accommodate itself to strains exercised in different directions. A simple 70

and effective way of providing this pivotal mounting is to make the casing with an opening *a*, receiving one of the wires of the frame, as shown at *b*, and thus the casing can have turning movement in a horizontal 75 plane. The pivotal end of the casing is held in position against vertical displacement by the wires *c*, *c'*, of the frame which are coiled at *c''* about the wire *b*. The casing lies within the side wire *d*, of the main 80 frame and between the same and the padding *e*, and with the vertical main wire *d'* close thereto on its inner side and thus the casing is held in its approximate position and is allowed a limited movement. The 85 padding will give sufficiently to allow the casing to swing inwardly until stopped by the vertical wire *d'*, it being understood that slight pivotal movement of the casing is sufficient to meet all requirements. Outward 90 swinging movement of the casing is limited by coming against the inner side of the wire *d* before mentioned. The casings are pivoted as stated, to the wires *b* and these wires form parts of the supplemental frames or 95 extensions, indicated generally at *f*, and extending out laterally beyond the main frame, and lying in front and outside of said main frame. The free ends of the pivotal casings lie in about the same vertical 100 plane as the rear face of the pad and by reason of mounting the casings on the supplemental frames at some distance in front of the main frames a considerable length of casing can be used to contain a spring of 105 adequate length and secure an appropriate length of yielding movement to suit different users.

The casings are formed open with an extension at *g*, which is simply turned over 110

at right angles to the axis of the casing in order to close the same. The front end of the casing wall is turned in to afford a bearing for the spring. I also have improved the frame of the mask by flattening and splitting certain of the wires at the end thereof and turning these split portions spirally around an adjacent wire or frame member to which the split wire must be attached. This provides a construction superior to that which would be afforded by welding or other forms of connection. This connection is illustrated at 6, which comprises the main portion of the split wire, and 15 7 and 8 indicate the ends which are split off from the end of the wire and turned spirally about the adjacent wire 9. This construction is carried out in connection with the eye wires and the vertical wires which serve 20 to brace and hold the eye wires. It is important that these eye wires be retained firmly in position and this improved construction attains this result.

It will be observed that the wires having 25 the split ends are turned from front to rear around the eye wires, thus bringing the main portions of said split wires toward the front with the coiled split portions lying close against the flattened main part of the 30 wire. The points or ends of the split portions lie in rear of the front faces of the eye wires and the separation between the coiled split ends occurs at the back of the frame so that the front of the frame is left 35 substantially free from projecting points or roughness.

What I claim is:—

1. In combination in a base-ball mask, a frame and a pad, a strap to pass around 40 the back of the head for holding the mask in position, and resilient connecting means between the strap and the frame of the mask, substantially as described.
2. In combination in a base-ball mask, a 45 frame and pad, an inelastic strap to pass around the back of the head for holding the mask in position, and resilient connecting means between the strap and the frame of the mask, substantially as described.
3. In combination in a base-ball mask, a 50 frame and pad, an inelastic strap to pass around the back of the head for holding the mask in position and a resilient connection between each end of the inelastic strap and the frame, substantially as described.
4. In combination in a base-ball mask, a 55 frame and pad, an inelastic strap to pass around the back of the head for holding the mask in position and a resilient connection between each end of the inelastic strap and the frame, said resilient connections comprising a rod, a holder, a spiral spring in the holder and exerting its force upon the rod, said rod being connected with the strap, 60 substantially as described.

5. In combination with a frame of a mask, a barrel at each side of the same directed rearwardly, a compression spring in each barrel and a rod in each borne upon by the spring and a strap to pass back of the head 70 having its ends attached to the said rods, substantially as described.

6. In combination in a base-ball mask, a wire frame, a casing, a spring within the 75 casing, a strap connected with the spring to pass around the head of the user, said casing being supported by a plurality of the wires of the frame at separated points, substantially as described.

7. In combination in a base-ball mask, a 80 wire frame, a pad, a casing containing a spring, and a strap connected with the spring, said casing being mounted on the frame at one point, and extending between the pad and a wire of the frame at another 85 point, substantially as described.

8. In combination in a base-ball mask, a wire frame, a pad, a casing containing a 90 spring and a strap connected with said spring to go around the user's head, said casing being mounted on one of the wires of the frame and confined against displacement by other wires of the frame, substantially as described.

9. In combination in a base-ball mask, a 95 wire frame, a pad carried thereby, a casing containing a spring, a strap connected with the spring to go around the user's head, said casing being pivotally mounted on one of the wires of the frame, substantially as described.

10. In combination in a base-ball mask, a wire frame, a pad carried thereby, a casing containing a spring, a strap connected with the spring to go around the user's head, said 105 casing being pivotally mounted on one of the wires of the frame, and confined by other wires of the frame, substantially as described.

11. In combination in a base-ball mask, a 110 wire frame, a casing containing a spring, a strap connected with said spring to pass around the user's head, said casing having an opening through which one of the frame wires extend to hold the casing in place, substantially as described.

12. In combination in a base-ball mask, a wire frame, a pad carried by the frame, a supplemental frame in front of the main frame, a casing connected with one of the wires of the supplemental frame and extending rearwardly therefrom, a spring in the casing and a strap connected with the spring, substantially as described.

13. In combination in a base-ball mask, a 125 wire frame, a pad carried by the frame, a supplemental frame in front of the main frame, a casing connected with one of the wires of the supplemental frame and extending rearwardly therefrom, a spring in 130

the casing and a strap connected with the spring, said casing extending between the wires of the main frame, substantially as described.

- 5 14. In combination in a base-ball mask, a wire frame, a pad carried by the frame, a casing containing a spring, a strap connected with the spring, said casing being held between horizontal wires of the frame at one 30
10 point, and being controlled by a vertical wire of the frame at another point, substantially as described.

- 15 15. In combination in a base-ball mask, a wire frame, a pad connected with the frame, a supplemental frame connected with the main frame, a casing having one end mounted on a vertical wire of the supplemental frame, and between horizontal wires thereof and extending rearwardly therefrom 35
20 between vertical wires of the main frame, said casing having pivotal movement, a spring within said casing and a strap connected to said spring, substantially as described. 40
25 16. In combination in a base-ball mask, a pad, a wire frame, one member of which has its end split and with the split ends turned around an adjacent wire, on opposite sides 45
50

of the main part of the split wire, substantially as described.

17. In combination in a base-ball mask, a pad, a frame comprising wires substantially at right angles, certain of said wires being flattened at the ends and split at said flattened portions with the split ends turned about the adjacent wire, substantially as described. 55

18. In combination in a base-ball mask, a pad, a wire frame, one member of which has its ends split and turned around an adjacent wire from front to rear and on opposite sides of the main part of the split wire, substantially as described. 60

19. In combination in a base-ball mask, a wire frame, a pad, an inelastic strap to pass around the user's head and a resilient connection between the strap and the frame, movably mounted on the frame to accommodate itself to strains in different directions, substantially as described. 65
50

In testimony whereof, I affix my signature.

JOSEPH M. SCHAEFER.
